(57) **CLAIM**

The ornamental design for a combination candlestick and bud vase, as shown and described.

DESCRIPTION

FIG. 1 is a first perspective view of the combination of the present invention, of my new design, showing the upper arm having a bud vase.

FIG. 2 is a first elevational view of the combination shown in FIG. 1, shown rotated about a horizontal axis of the combination, further showing two arms having candlestick receiving openings.

FIG. 3 is a top view of the combination shown in FIG. 2; and,

FIG. 4 is a second perspective view of the combination shown in FIG. 1, shown rotated about a horizontal axis of the combination.
